United States Patent Office

Des. 188,035

Patented May 31, 1960

188,035

MITT

John H. Mackay, Jenkintown, and Dean K. Schleicher, Plumsteadville, Pa., assignors of twenty-five percent to said Mackay, twenty-five percent to said Schleicher, twenty-five percent to Naomi C. May, and twenty-five percent to Joseph A. Sutton, both of Philadelphia, Pa.

Filed Feb. 20, 1959, Ser. No. 54,691

Term of patent 14 years

(Cl. D3—11)

The drawing has been lined for color.

We claim:

The ornamental design for a mitt, as shown and described.
